United States Patent Office.

GEORGE M. BRIGGS, OF BOSTON, NEW YORK.

Letters Patent No. 62,930, dated March 19, 1867.

IMPROVEMENT IN WOOL PRESSES.

The Schedule referred to in these Letters Patent and making part of the same.

TO ALL WHOM IT MAY CONCERN:

Be it known that I, GEORGE M. BRIGGS, of Boston, in the county of Erie, and State of New York, have invented a new and improved Press for Baling Wool Fleeces; and I do hereby declare that the following is a full and exact description thereof, reference being had to the accompanying drawings, making part of this specification, in which—

Figure 1 is a plan view of my improved apparatus in position for receiving a fleece.

Figure 2 is a longitudinal vertical section of the same in the position for imparting the final pressure to the fleece preparatory to tying.

Figure 3 is a transverse vertical section in the plane of line $z z$, fig. 2.

Like letters of reference indicate corresponding parts in all the figures.

My invention is designed for making up the fleeces into compact and separate bundles, as shorn, and consists of a frame, provided with adjustable wings or sections, which, by being turned up, fold the fleece so as to enclose it in a trough or way which they form, and in which a follower, operated by suitable mechanism, compresses the fleece at one end of the machine in a compact body for tying; and also in the arrangement of several strands of twine in suitable grooves, crossing each other at right angles under the compressed fleece, so as to properly tie the same, with suitable receptacles beneath the apparatus for holding the balls of twine.

As shown in the drawings, A A are strips of plank, or other suitable timber, placed side by side, leaving a small space, a , between each, for the strands of twine, and secured at their ends to a suitable frame or supports, B B, of convenient height. These strips should be a little longer than the length of a large fleece, and together, as arranged side by side, of a width equal to that of the bale required to be made with the fleece. To the two outer strips A A are hinged, so as to enable them to turn up in a vertical position, the wings C C, which, when horizontal, as shown in fig. 1, form a table or platform, upon which the fleece is laid for folding. At one end of the apparatus short pieces D D, corresponding in width with A A, and of a length equal to the width of the wings C C, are placed upright, and permanently secured in any suitable manner so as to form a continuation and end of the trough formed by the wings C C, when turned up, wherein the fleece receives its final compression preparatory to tying. Across the ends of A A, in their upper side, are formed grooves or recesses $b b$, in line with and of a width equal to the spaces between the pieces D D, in which are placed strands of twine $c c$. The follower E, as shown, is preferably constructed of two pieces of plank, F and G, placed above and beneath the strips A A, and connected together by thin pieces or lips $d d$, passing through and sliding in the space $a a$, and fastened to each of the former in any suitable manner. To the plank F are properly fastened upright portions H H, which correspond in size and position with the end pieces D D, so that, when the follower is moved forward, as shown in fig. 2, it will form with D D the four sides of a square box in which the fleece is pressed. The follower may be operated by the following mechanism: I is an axle, placed transversely of the machine under that end of A A where the bundle is formed, and having at one end a winch, e, by which it is operated, and a ratchet-wheel, f, and pawl, g, by which it is held in any desired position. To one end of this axle is secured the rope or band h, which is wound a sufficient number of times around it to allow the follower the necessary backward movement, the end of the rope connecting with the front edge of G. To the rear or opposite edge of G a similar rope, i, is fastened, which extends around a pulley, J, which is mounted in any suitable manner at the centre of the rear end of the machine, (shown in fig. 2,) and thence forward, where it is wound around and secured to the axle I, in the opposite direction, in a manner similar to that of h at its other end. By turning the axle the follower E is made to advance or recede, by sliding along the horizontal strips A A according to the direction in which the axle is revolved. Underneath the apparatus is constructed a number of boxes for holding the balls of twine used in tying the bales or packages, of which I prefer to use, as most convenient, six, numbered 1 to 6 inclusive, one for each strand employed.

The operation of my improvements is simple and obvious. The strands $t t$ and $c c$ are first placed in the spaces and grooves $a a$ and $b b$, as shown in fig. 1. The apparatus being in the position represented in the same figure, the wings spread out and forming a convenient table, and the follower being at the rear of the machine, the fleece is spread upon the former. Its sides being turned in, the wings C C are raised to a vertical position, by which act the fleece is folded into a roll lying longitudinally on the central portion A A. The wings being secured in this position to D D by means of catch-bolts $s s$, or other suitable means. The tag ends of the roll are

turned in, and the follower caused to advance, by turning the winch *e*, which forces and compresses the fleece towards the opposite end, where it receives its final pressure in the square box, formed as before described, and shown in fig. 2. The compact mass is now secured with great facility, by bringing up the ends of the strings *c c* and *t t* successively, and tying them on top, when the follower is reversed, leaving the bundle in a most regular and compact form for handling and stowing-away. The twine is again fixed in place, when the apparatus is ready for a second fleece.

The advantages of my invention are as follows: The ease and rapidity with which a fleece may be tied up; the regular and square form and compactness of the bundle; the mode of compression by means of the follower does not separate the fibres of the fleece, as in the ordinary method of folding, but packs them together in the natural position in which they are when first removed from the sheep; the spaces for the twine, in combination with the separate boxes 1, 2, 3, 4, 5, 6, for the balls, prevent its becoming entangled, and keep each strand in the place required, thereby greatly expediting the process of tying.

What I claim as my invention, and desire to secure by Letters Patent, is—

The separate twine receptacles 1, 2, 3, 4, 5, 6, and corresponding grooves *a a a* and *b b b*, when combined and arranged with the stationary bed A A, fixed compressing box D D, and follower E, substantially in the manner and for the purposes described.

In witness whereof I have hereunto signed my name in the presence of two subscribing witnesses.

GEORGE M. BRIGGS.
